PORTABLE MOLDING SAND MULLER, INCLUDING SUSPENDABLE POWER-DRIVEN MULLER UNIT AND UNDERLYING PORTABLE BOWL RECEPTACLE

Walter F. Piper and Joseph J. Soldat, Chicago, Ill., assignors, by mesne assignments, to Pettibone Mulliken Corporation, a corporation of Delaware

Application April 24, 1944, Serial No. 532,445

13 Claims. (Cl. 241—100)

1

The present invention relates generally to mulling apparatus. More particularly the invention relates to that type of apparatus which is designed primarily to be used in a foundry to mull molding sand in order properly to condition it preparatory to use in flasks, and as its main component parts comprises (1) an open top bowl-like receptacle which is adapted to receive and retain a batch of sand to be milled; (2) a rotary horizontally extending crosshead which is connected for drive by an electric motor through the medium of speed reducing gearing; and (3) a mulling element which is mounted on the crosshead and is adapted in connection with drive of the latter to travel around the receptacle and effect mulling of the sand by squeezing it against the receptacle.

One object of the present invention is to provide a sand mulling apparatus of this type which is especially adapted for use in a small sized foundry and is characterized by the fact that the receptacle is mounted on wheels and the rotary crosshead, the crosshead driving electric motor and speed reducing gearing, and the mulling element are in the form of a self-contained unit which is provided with means whereby it may be raised and lowered and is adapted to be lowered onto the receptacle in connection with a sand mulling operation and is further adapted to be raised above the receptacle at the conclusion of a sand mulling operation in order to permit the receptacle to be wheeled to the location where the milled or conditioned sand is to be used.

Another object of the invention is to provide a sand mulling apparatus of the last mentioned character in which the wheel equipped receptacle is in the form of a wheelbarrow whereby it may be readily transported to and from the vertically movable self-contained mulling unit.

Another object of the invention is to provide a sand mulling apparatus of the type and character under consideration in which the self-contained mulling unit embodies a continuous side wall which surrounds the rotary crosshead and mulling element, is adapted when the unit is lowered into its operative position with respect to the wheelbarrow to rest on, and form a continuation, of, the side wall of the receptacle part of the wheelbarrow, and has means for guiding it into registering relation with the side wall of the receptacle part of the wheelbarrow and also has means for clamping its lower margin to the upper margin of the side wall of the receptacle part of the wheelbarrow.

A further object of the invention is to provide

2

a sand mulling apparatus of the type and character heretofore mentioned in which the self-contained mulling unit is provided with an upstanding bail whereby it may be attached to the hook of an overhead hoisting apparatus in order that it may be raised and lowered thereby, and the mulling element is in the form of a rotatably supported wheel and is connected to, and carried by, the crosshead in a novel manner.

10 Another object of the invention is to provide a sand mulling apparatus which is generally of new and improved construction, has certain advantages over previously designed sand mulling apparatus, effectively and efficiently fulfills its intended purpose, and is so designed and constructed that it may be produced at a low and reasonable cost.

Other objects of the invention and the various advantages and characteristics of the present sand mulling apparatus will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a side elevation showing a sand mulling apparatus embodying the invention with the self-contained mulling unit in raised relation with respect to the wheelbarrow;

Figure 2 is a vertical section showing the mulling unit in its lowered or operative position with respect to the receptacle part of the wheelbarrow and illustrating in detail the construction and design of the speed reducing gearing for driving the rotary crosshead from the electric motor;

Figure 3 is a section taken at right angles to Figure 2 and illustrating in detail the design and arrangement of the crosshead and the manner of mounting the wheels constituting the means for effecting mulling of the sand by squeezing it against the receptacle part of the wheelbarrow;

Figure 4 is a plan view of the apparatus; and

Figure 5 is a horizontal section on the line 5—5 of Figure 2.

The mulling apparatus which is shown in the drawings constitutes the preferred form or embodiment of the invention. It is designed primarily for use in a foundry or like establishment, serves as a medium or instrumentality for mulling sand in order properly to condition it

preparatory to use in flasks, and comprises a wheelbarrow 6 and a vertically movable self-contained mulling unit 7. As hereinafter described more in detail the unit is adapted in connection with a mulling operation, to be lowered onto the wheelbarrow. It is further adapted after a mulling operation, to be raised into an inoperative position in order to free the wheelbarrow so that it may be wheeled or transported to the location or station where the mulled sand is to be used.

The wheelbarrow 6 comprises a frame structure 8, a pair of ground wheels 9, and a receptacle 10. The frame structure 8 embodies a pair of laterally spaced, parallel, vertically extending sides 11, a nose piece 12, a rear wall 13, and a pair of U-shaped legs 14. The sides 11 are formed of plate metal and are cross connected by the nose piece 12 and the rear wall 13. They have the front lower corners thereof cut away as shown in Figures 1 and 2, and embody arcuate cutouts 15 in their upper margins. The nose piece 12 is formed of channel shaped metallic stock and has the ends thereof welded or otherwise rigidly secured to the front portions of the sides 11. The rear wall 13 extends vertically and has its ends jointed to, and formed integrally with, the rear end margins of the sides 11. The legs 14 are formed of angle bars and have the upper ends welded to the lower rear corners of the sides 11 of the frame structure 8. In addition to the parts heretofore mentioned the frame structure embodies a pair of laterally spaced substantially horizontal handles 16. The front ends of these handles fit within, and are bolted to, tubular metallic pieces 17 which, as shown in Figures 1 and 4, are welded to the upper rear corners of the sides 11. The rear ends of the handles are bent downwards in order to provide hand grips. The wheels 9 are disposed outwards of the sides 11 and are located in front of the legs 14. They preferably are provided with pneumatic tires 18 and are mounted on the ends of a horizontal axle 19. The latter is disposed in parallel relation with the rear wall 13 of the frame structure 8 and has the portions thereof that are directly inwards of the wheels disposed in, and welded to, semicircular recesses 20 in the lower central portions of the sides 11. The receptacle 10 is preferably formed of plate metal and consists of a dished or downwardly bulged bottom 21 and an upstanding cylindrical side wall 22. The receptacle bottom 21 extends transversely across the sides 11 of the frame structure 8 and has portions thereof disposed in the arcuate cutouts 15. Such portions are welded to the edge portions of the sides that define the cutouts in order that the receptacle 10 is in fixed or rigid relation with the frame structure 8. The receptacle side wall 22 is formed integrally with the marginal portion of the bottom 21 and its reinforced at its upper end by an angle bar type ring 23. The latter embodies a horizontal leg 24 and a vertical leg 25. The horizontal leg projects outwards from, and is aligned with, the upper edge of the receptacle side wall 22, as shown in Figures 2 and 3. The vertical leg 25 of the ring 23 depends from the inner marginal portion of the horizontal leg 24 and is welded or otherwise fixedly secured to the outer surface of the upper end of the receptacle side wall 22. The wheels 9 and the legs 14 of the wheelbarrow serve to support the receptacle 10 in an elevated position with respect to the subjacent floor. The wheels permit the wheelbarrow to be wheeled to any desired location in the foundry. It is con-

templated that the receptacle 10 will be filled with a batch of sand to be mulled and then the wheelbarrow will be wheeled under the self-contained mulling unit 7. After the wheelbarrow is wheeled under the unit it is released by the operator so that the legs thereof rest on the floor. Thereafter the mulling unit is lowered onto the receptacle and is then operated so as to effect mulling of the sand in the receptacle. After 10 a mulling operation the mulling unit is raised and the wheelbarrow is wheeled to the location where the mulled sand is to be used.

The self-contained mulling unit 7 is preferably supported for vertical movement to and from the wheelbarrow by way of an overhead travelling crane C comprising a horizontally extending bridge c and a carriage c¹. The carriage is mounted for travel back and forth on the bridge and embodies hoisting means in the form of a motor operated drum and a cable. One end of the cable is anchored to, and extends around, the drum and the other end of the cable is provided with a hook c². The unit 7 comprises a cylindrical side wall 26, a horizontally extending rotary crosshead 27, and a pair of mulling wheels 28.

The side wall 26 surrounds the crosshead 27 and the mulling wheels 28 and is the same in diameter as the side wall 22 of the wheelbarrow receptacle 10. It is formed of plate metal and has a reenforcing ring 29 around its lower end and a reenforcing ring 30 around its upper end. The reenforcing ring 29 is formed of angle bar stock and consists of a horizontally extending leg 31 and a vertically extending leg 32. The horizontally extending leg is flush with the lower end edge of the side wall 26 and is adapted to rest on the horizontally extending leg 24 of the reenforcing ring 23 when the mulling unit 7 is in operative relation with the wheelbarrow 6. The vertically extending leg 32 of the reenforcing ring 29 extends upwards from the inner marginal portion of the horizontally extending leg 31 and surrounds, and is welded or otherwise fixedly secured to, the outer surface of the lower marginal portion of the side wall 26. The reenforcing ring 30 is formed of angle bar stock and consists of a horizontally extending leg 33 and a vertically extending leg 34. The horizontally extending leg 33 projects outwards from, and is flush with, the upper end edge of the side wall 26. The other leg of the ring 30, i. e., the vertically extending leg 34, is connected to, and depends from, the inner margin of the horizontally extending leg 33 and surrounds, and is welded or otherwise fixedly secured to, the outer surface of the upper marginal portion of the side wall 26. In order to guide the side wall 26 into registering or concentric relation with the receptacle side wall 22 when the unit 7 is lowered onto the wheelbarrow for a mulling operation a plurality of vertically extending guide plates 35 is provided. These guide plates are preferably three in number and are welded to, and positioned equidistantly around, the side wall 26. The lower ends of the guide plates 35 are in the form of fingers 36 and these project beneath the horizontally extending leg 31 of the reenforcing ring 29. The lower portions of the inner edges of the fingers 36 are bevelled and serve to cam the side wall 26 of the mulling unit 7 into registering or concentric relation with the receptacle side wall 22 when the unit is lowered onto the wheelbarrow. When the unit 7 is in place the depending fingers 36 straddle the horizontally extending leg 24 of the reenforcing ring 23 at the upper end

of the receptacle side wall 22 and thus maintain the side wall 26 against horizontal displacement with respect to the receptacle side wall 22. In addition to the reenforcing rings and guide plates the side wall 26 of the mulling unit is provided with a plurality of latches 37. These latches correspond in number to, and are associated respectively with, the finger equipped guide plates 35 and consist of horizontally extending L-shaped latch members 38 and vertically extending pivot bolts 39. The latch members 38 are carried by the pivot bolts 39 so that they are capable of swinging in a horizontal plane. They are disposed directly beneath the horizontally extending leg 31 of the reenforcing ring 23 and consists of 15 outer handle type arms 40 and inner arms 41. The inner arms are joined to the inner ends of the outer arms and extend at right angles to said outer arms. They are provided with bevelled or canted upper surfaces and are adapted when the latch members 38 are turned in a clockwise direction as viewed in Figure 4 to swing into an operative position wherein they underlie and engage the horizontally extending leg 24 of the reenforcing ring 23 at the upper end of the receptacle side wall 22, and serve to lock the mulling unit 7 to the wheelbarrow. When the latch members 38 of the latches 37 are turned in the opposite direction the inner arms 41 swing out of engagement with the horizontally extending leg of the reenforcing ring 23 and thus release the unit 7 so that it may be raised with respect to the wheelbarrow. The vertically extending pivot bolts 39 extend through holes in the portions of the latch members 38 where the outer and inner arms are joined together. As shown in Figures 1 and 2, the bolts 39 are arranged so that the heads thereof are at the bottom and underlie the latch members 38. The shanks of the bolts 39 extend loosely through sleeve-like members 42 on the guide plates 35 and have nuts 43 at their upper extremities. Spiral compression springs 44 are interposed between the nuts 43 and the upper ends of the sleeve-like members 42 and serve to urge the latch members 38 upwards. The members 42 are preferably welded to the guide plates 35 and are located directly opposite the horizontally extending leg 31 of the reenforcing ring 23. The latches 37 exemplify simple means for releasably locking the side wall 26 of the mulling unit 7 to the side wall 22 of the wheelbarrow receptacle 10. Two laterally spaced parallel horizontal angle bars 45 extend across the upper end of the cylindrical side wall 26. These angle bars consist of horizontally extending legs 46 and vertically extending legs 47. The horizontally extending legs 46 are joined to, and project inwards from, the lower margins of the vertically extending legs 47 and have the ends thereof welded or otherwise fixedly secured to the horizontally extending leg 33 of the reenforcing 39. A bail 48 serves to connect the mulling unit 7 to the hook c² of the carriage of the overhead travelling crane C. The lower ends of the legs of the bail are provided with attaching plates 49 and these are welded to the vertically extending legs 47 of the angle bars 45. The bail is arranged so that when the unit 7 is supported from the hook c² it will assume a position wherein the axis of the cylindrical side wall 26 is vertical.

The crosshead 27 carries and serves to revolve the mulling wheels 28 and is surrounded by the cylindrical side wall 26. It extends horizontally for the most part and is fixedly connected to the lower end of a vertically extending drive shaft

50. An electric motor 51 operates, through the medium of speed reducing gearing 52, to drive the crosshead so that the latter, in turn, causes the mulling wheels to travel around the bottom of the wheelbarrow receptacle 10 and thus effect mulling of the batch of sand in the receptacle. As shown in Figures 2 and 3, the drive shaft 50 is centrally disposed with respect to the cylindrical side wall 26 of the mulling unit 7 and is journalled in a vertically elongated bearing 53. The upper end of the bearing is bolted to the bottom wall of a sectional housing 54 for the speed reducing gearing 52. The housing is horizontally elongated and consists of a lower section 55 and an upper section 56. The lower section extends between the angle bars 45 and has side lugs 57 which rest upon, and are bolted to, the horizontally extending legs 46 of the angle bars 45. The upper section 56 of the housing is removably connected to the lower section 55 by the bolts which serve to connect the side lugs 57 to the angle bars 45. The upper end of the drive shaft 50 extends into one end of the housing 54. The electric motor 51 is mounted on the top wall of the upper section 56 of the housing 54. It is positioned in offset relation with the drive shaft 50 and is arranged so that the armature shaft thereof extends vertically. The lower end of the casing of the motor rests on, and is bolted to, said top wall of the upper section of the housing 54. The lower end of the armature shaft of the motor projects into the other end of the housing for the speed reducing gearing 52. The latter, as shown in Figure 2, comprises a pinion 58, a gear 59, a pinion 60, a gear 61, a pinion 62 and a gear 63. The pinion 58 is keyed or otherwise fixedly secured to the lower end of the armature shaft of the electric motor 51 and meshes with, and serves to drive, the gear 59 in response to operation of the motor. The gear 59 is loosely mounted on the upper end of the drive shaft 50. The pinion 60 is disposed beneath, and fixedly secured to, the gear 59. It extends loosely around the upper end of the drive shaft 50 and meshes with, and serves to drive, the gear 61. The latter is mounted rotatably on the upper end of a vertically extending stub shaft 64 which is axially aligned with the armature shaft of the motor and has its lower end fixedly secured in a socket 65 in the bottom wall of the lower section 55 of the housing 54. The pinion 62 is located beneath, and connected for drive by, the gear 61 and meshes with, and serves to drive, the gear 63. The latter is located beneath the pinion 60 and is fixedly connected to the drive shaft 50. When the electric motor 51 is in operation it operates to drive the speed reducing gearing 52 and the latter, in turn, operates to rotate the crosshead 27 and effect drive of the mulling wheels 28. Electric current is supplied to the electric motor 51 by way of a flexible conductor (not shown). A switch 66 on the casing of the electric motor 51 serves to control the supply of current to the motor. As shown in Figure 3, one end of the crosshead 27 is bent downwards to provide an arm 67 adjacent the inner periphery of the cylindrical side wall 26.

The mulling wheels 28 are located at opposite sides of the crosshead 27 and are adapted in connection with a mulling operation, i. e., when the receptacle 10 is charged with a batch of sand and the mulling unit and wheelbarrow are in their operative position, to travel in a circular course over the receptacle bottom 21 and effect mulling of the sand by squeezing it against the bottom of the re-

ceptacle. They comprise circular bodies 68 and solid rubber tires 69 around the bodies and are rotatably mounted on the ends of an axle 70 which underlies the drive shaft 50 and extends at right angles to the crosshead 27. The central portion of the axle 70 is welded to the central portion of a bar 71 which, as shown in Figure 3, is spaced beneath, and is in parallel relation with, the crosshead 27. The end of the bar 71 that is adjacent the down bent arm 67 is connected to the superjacent portion of the crosshead 27 by way of a vertically extending bolt 72. The bolt is arranged so that the head thereof is at the bottom and abuts against the bottom surface of the bar 71. The upper end of the shank of the bolt extends through an oversized hole 73 in the crosshead 27 and is provided with a pair of nuts, one of which abuts against the top face of the crosshead. A collar shaped block 74 of rubber or like resilient material surrounds the central portion of the shank of the bolt 72 and is interposed between the bar 27 and the bar 71. The bolt 72 permits the bar together with the mulling wheels 28 to swing vertically to a limited extent. Downward swinging of the bar is limited by way of a crosspin 75 on the lower end of a vertically extending bar 76. Such bar extends through an oversized hole 77 in the distal end of the bar 71 and has its upper end welded to the end of the crosshead 27 that is opposite the arm 67. The pin 75 extends transversely through the lower end of the vertically extending bar 76. It is of such length that the ends thereof serve as stops or abutments for limiting downward swing of the bar 71. The bar 71 is urged downwards by way of a spiral compression spring 78 in order to force the mulling wheels 28 toward the bottom of the wheelbarrow receptacle 10. The lower end of the spring 78 abuts against the distal end of the bar 71 and the upper end of the spring abuts against a horizontally extending plate 79 which is connected to the upper end of an upstanding bar 80. The last mentioned bar overlies the bar 76 and has its lower end welded to the crosshead 27. When the mulling unit 7 is raised with respect to the wheelbarrow the distal end of the bar 71 rests on, and is supported by, the crosspin 75. When the unit is lowered into its operative position with respect to the wheelbarrow 6 the wheels 28 cause the bar 71 to swing upwards after they are brought into engagement with the receptacle bottom 21 of the wheelbarrow. When the unit and wheelbarrow are in their operative position the compression spring 78 exerts downward pressure on the wheels with the result that the wheels, in connection with travel over the receptacle bottom, effect the desired squeezing of the sand. As shown in Figures 2, 4 and 5, one of the wheels is farther from the drive shaft 50 than the other wheel. As the result of this the wheels in connection with a mulling operation, traverse different circular zones of the bottom 21 of the wheelbarrow receptacle 10. The bottom surface of the rubber block 74 is canted, as shown in Figure 2, in order that the bar 71 supports the axle 70 in such an angular position that the two mulling wheels are properly positioned with respect to the circular zones of the receptacle bottom wall which they respectively traverse. As shown in the drawings, the upper portions of the mulling wheels are disposed within the cylindrical side wall 26 and the lower portions of the wheels are disposed beneath said side wall.

In addition to the side wall 26, the crosshead 27, the mulling wheels 28 and the other parts heretofore mentioned the mulling unit 7 comprises a

scraper 81 and a plow 82. The scraper 81 is bolted to the lower end of the crosshead arm 67 and is arranged and designed to scrape the side wall 22 and the outer portion of the bottom 21 of the wheelbarrow receptacle 10 during a sand mulling operation. As shown in Figure 4, the scraper 81 is angularly disposed with respect to the crosshead 27 and so positioned that the leading and bottom edges thereof are positioned immediately adjacent the inner face of the receptacle side wall and the outer portion of the receptacle bottom wall when the mulling unit 7 is in its operative position with respect to the wheelbarrow 6. The plow 82 is in the form of a curved plate and is connected to the lower end of the vertically extending bar 76 by a bracket 83. It is adapted during a mulling operation to force sand in the central portion of the receptacle outwards into the path of the mulling wheels. The lower edge of the plow is curved conformably to the bottom 21 of the receptacle 10. The scraper 81 serves to scrape the sand inwards and the plow 82 operates to force the sand outwards.

When it is desired to use the apparatus the wheelbarrow is first charged with a batch of sand to be mulled. It is then wheeled under the mulling unit 7 while the latter is in its raised position. After the wheelbarrow is brought to rest under the unit the unit is lowered until the horizontally extending leg 31 of the reenforcing ring 29 on the lower end of the side wall 26 rests on the horizontally extending leg 24 of the reenforcing ring 23 on the receptacle side wall. During downward shift of the unit the depending fingers 36 on the lower ends of the guide plates 35 serve automatically to center the side wall 26 with respect to the side wall 22 of the receptacle. After lowering of the unit the latch members 38 of the latches 37 are swung so as to bring the inner arms 41 of the members 38 into gripping relation with the horizontally extending leg 24 of the ring 23. As soon as the latch members 38 are in their operative position the unit 7 is locked to the wheelbarrow. After locking of the unit to the wheelbarrow the electric motor 51 is started by closing the switch 66. As soon as the motor is in operation the crosshead 27 is caused to revolve and operates, through the medium of the bar 71 and the axle 70, to drive the mulling wheels 28 so that they travel in a circular course over the receptacle bottom 21. During travel of the wheels in such circular course the wheels revolve about the axle and effect mulling of the sand by squeezing it against the receptacle bottom. In connection with drive of the crosshead the scraper 81 on the crosshead arm 67 scrapes the sand inwards from the receptacle side wall 22 and the plow 82 forces the sand in the central portion of the receptacle outwards into the path of the mulling wheels. By reason of the fact that the wheels are urged downwards by the compression springs 78 the sand, in connection with a mulling operation, is subjected to a pronounced squeezing action. At the conclusion of the mulling operation the latches 37 are released by swinging the latch members 38 so as to disengage the inner arms 41 thereof from the horizontally extending leg 24 of the ring 23. After release of the latches the mulling unit 7 is raised by manipulation of the hoisting means on the carriage 41 of the overhead travelling crane C. After raising of the unit 7 the wheelbarrow is wheeled to the location or station where the mulled sand is to be used.

The herein described mulling apparatus is simple in design and hence may be manufactured

at a low and reasonable cost. It effectively and efficiently fulfills its intended purpose and is especially designed for use in a small sized foundry.

Whereas the apparatus has been described as being primarily designed or adapted for mulling molding sand it is to be understood that the apparatus may be used for mulling or conditioning other material. It is also to be understood that the invention is not to be restricted to the details set forth since these may be modified within the scope of the appended claims without departing from the spirit and scope of the invention.

Having thus described the invention what we claim as new and desire to secure by Letters Patent is:

1. An apparatus adapted for use in mulling molding sand in a foundry having an overhead hoisting apparatus, and comprising a portable bowl-shaped receptacle for the sand to be mulled, and a self-contained mulling unit provided with means whereby it may be attached to the hoisting apparatus in order that it may be bodily lowered and raised by said hoisting apparatus into and out of an operative position with respect to the receptacle when the latter is positioned therebeneath and embodying a continuous side wall shaped conformably to the side wall of the receptacle and adapted when the unit is in its operative position to rest on, and form a continuation of, the receptacle side wall, a rotary member disposed within the continuous side wall, an upstanding mulling wheel carried by the member, having the upper portion thereof disposed within the continuous side wall and its lower portion disposed beneath said continuous side wall, and arranged so that during drive of the member while the unit is in its said operative position it travels in a circular course over the receptacle and effects mulling of the sand by squeezing it against the receptacle, and power means in the form of an electric motor and speed reducing gearing for driving the rotary member.

2. An apparatus adapted for use in mulling molding sand in a foundry having an overhead hoisting apparatus, and comprising a portable bowl-shaped receptacle adapted to contain a batch of the sand to be mulled and provided with an upstanding cylindrical side wall, and a self-contained mulling unit provided with means whereby it may be detachably connected to the hoisting apparatus in order that it may be bodily lowered and raised by said hoisting apparatus into and out of an operative position with respect to the receptacle when the latter is positioned therebeneath, and embodying a cylindrical side wall of substantially the same diameter as the receptacle side wall and adapted when the unit is in its operative position to rest on, and form a continuation of, said receptacle side wall, a rotary member disposed within the second mentioned side wall, an upstanding mulling wheel connected to the member so that it is movable vertically to a limited extent relatively thereto, having the upper portion thereof disposed within the second mentioned side wall and its lower portion disposed beneath said second mentioned side wall, and arranged so that during drive of the member while the unit is in its said operative position it travels in a circular course over the receptacle and effects mulling of the sand by squeezing it against the receptacle, and power means in the form of an electric motor and speed reducing gearing for driving the rotary member.

3. An apparatus adapted for use in mulling molding sand in a foundry having an overhead

hoist, and comprising a portable bowl-shaped receptacle adapted to contain a batch of the sand to be mulled and provided with ground wheels whereby it may be wheeled from place to place, and a self-contained mulling unit provided with means whereby it may be attached to the hoisting apparatus in order that it may be lowered and raised by said hoisting apparatus into and out of an operative position with respect to the receptacle when the latter is positioned therebeneath and embodying a continuous side wall shaped conformably to the side wall of the receptacle and adapted when the unit is in its operative position to rest on, and form a continuation of, the receptacle side wall, a rotary member disposed within the continuous side wall, an upstanding mulling wheel connected to the member, having the upper portion thereof disposed within the continuous side wall and its lower portion disposed beneath said continuous side wall, and arranged so that during drive of the member while the unit is in its said operative position it travels in a circular course over the receptacle and effects mulling of the sand by squeezing it against the receptacle, and power means for driving the rotary member.

4. A mulling apparatus comprising a wheelbarrow having a bowl-shaped receptacle adapted to contain a batch of the material to be mulled and provided with a continuous upstanding side wall, and a self-contained mulling unit provided with means whereby it may be lowered and raised into and out of an operative position with respect to the wheelbarrow when the latter is positioned therebeneath, and embodying a continuous side wall shaped conformably to the receptacle side wall and adapted when the unit is in its operative position to rest on, and form a continuation of, said receptacle side wall, a rotary member disposed within the second mentioned continuous side wall, an upstanding mulling wheel connected to the rotary member so that it is movable vertically to a limited extent relatively thereto, having the upper portion thereof disposed within the second mentioned continuous side wall and its lower portion disposed beneath said second mentioned continuous side wall, provided with spring means for urging it downwards, and arranged so that during drive of the member while the unit is in its operative position it travels in a circular course over the receptacle and effects mulling of the material by squeezing it against the receptacle, and power means for driving the rotary member.

5. An apparatus adapted for use in mulling material in an establishment having an overhead hoisting apparatus with a flexible depending hoist element, and comprising a portable bowl-shaped receptacle for the material to be mulled; a self-contained mulling unit provided with means whereby it may be connected to, and freely suspended from, the lower end of the hoist element in order that it may be lowered and raised by the hoisting apparatus into and out of an operative position with respect to the receptacle when the latter is positioned therebeneath, and embodying a continuous side wall shaped conformably to the side wall of the receptacle and adapted when the unit is in its operative position to rest on, and form a continuation of, the receptacle side wall, a rotary member disposed within the second mentioned side wall, an upstanding mulling wheel carried by the member positioned so that the upper portion thereof is disposed within the second mentioned side wall and its lower portion is

disposed beneath said second mentioned side wall, and arranged so that during drive of the latter while the unit is in its said operative position it travels in a circular course over the receptacle and effects mulling of the material by squeezing it against the receptacle, and power means in the form of an electric motor and speed reducing gearing for driving the rotary member; and means for guiding the side wall of the unit into registering relation with the receptacle side wall when the unit is lowered into its operative position.

6. An apparatus adapted for use in mulling material in an establishment having an overhead hoisting apparatus with a flexible depending hoist element, and comprising a portable bowl-shaped receptacle for the material to be mulled, and a self-contained mulling unit provided with means whereby it may be detachably connected to, and freely suspended from, the lower end of the hoist element in order that it may be lowered and raised by said hoisting apparatus into and out of an operative position with respect to the receptacle when the latter is positioned therebeneath, and embodying a continuous side wall shaped conformably to the side wall of the receptacle, adapted when the unit is in its operative position to rest on, and form a continuation of the receptacle side wall, and provided with depending fingers at its lower end for guiding it into registering relation with the receptacle side wall when the unit is lowered into its operative said position, a rotary member disposed within the second mentioned side wall and provided with an element that is adapted during drive of the member while the unit is in its said operative position to travel in a circular course in the receptacle and effect mulling of the material, and power means for driving the rotary member.

7. An apparatus adapted for use in mulling material in an establishment having an overhead hoisting apparatus, and comprising a portable bowl-shaped receptacle for the material to be mulled, and a self-contained mulling unit provided with means whereby it may be attached to the hoisting apparatus in order that it may be bodily lowered and raised by said hoisting apparatus into and out of an operative position with respect to the receptacle when the latter is positioned therebeneath, and embodying a continuous side wall shaped conformably to the side wall of the receptacle, adapted when the unit is in its operative position to rest on, and form a continuation of, the receptacle side wall, and provided with latch means for releasably locking it to the receptacle side wall when the unit is in its said operative position, a rotary member disposed within the second mentioned side wall, an upstanding mulling wheel carried by the member, having the upper portion thereof disposed within the second mentioned side wall and its lower portion disposed beneath said second mentioned side wall, and arranged so that during drive of the latter while the unit is in its said operative position it travels in a circular course over the receptacle and effects mulling of the material by squeezing it against said receptacle, and power means for driving said rotary member.

8. An apparatus adapted for use in mulling material in an establishment having an overhead hoisting apparatus with a flexible depending hoist element, and comprising a portable bowl-shaped receptacle adapted to contain a batch of the material to be mulled and provided with ground wheels whereby it may be wheeled

from place to place, and a self-contained mulling unit provided with means whereby it may be detachably connected to, and freely suspended from, the lower end of the hoist element in order that it may be lowered and raised by said hoisting apparatus into and out of an operative position with respect to the receptacle when the latter is disposed therebeneath and embodying a continuous side wall shaped conformably to the side wall of the receptacle, adapted when the unit is in its operative position to rest on, and form a continuation of, the receptacle side wall, provided on its lower end with depending fingers for guiding it into registering relation with the receptacle side wall when the unit is lowered into its operative position, and also provided with a latch for releasably locking it to the receptacle side wall, a rotary member in the second mentioned side wall, a mulling wheel carried by the member and arranged so that during drive of the latter while the unit is in its said operative position it travels in a circular course within the receptacle and effects mulling of the material by squeezing it against said receptacle, and power means for driving said rotary member.

9. A mulling apparatus of the character described comprising a wheelbarrow having a bowl-shaped receptacle adapted to contain a batch of the material to be mulled and provided with a cylindrical upstanding side wall, and a self-contained mulling unit provided with means whereby it may be lowered and raised into and out of an operative position with respect to the receptacle when the latter is positioned therebeneath, and embodying a cylindrical side wall of substantially the same diameter as the receptacle side wall, adapted when the unit is in its operative position to rest on, and form a continuation of, the receptacle side wall, provided with depending means for guiding it into registering relation with the receptacle side wall when the unit is lowered into its operative position, and also provided on said means with latch means for releasably locking it to said receptacle side wall, a rotary crosshead in the second mentioned side wall, a mulling wheel carried by the crosshead and adapted during drive of the latter while the unit is in its operative position to travel in a circular course in the receptacle and effect mulling of the material, and power means for driving the crosshead.

10. An apparatus adapted to mull granular material in an establishment having an overhead hoisting apparatus, and comprising a portable bowl-shaped receptacle for the material to be mulled, and a self-contained mulling unit provided with means whereby it may be attached to the hoisting apparatus in order that it may be lowered and raised by said hoisting apparatus into and out of an operative position with respect to the receptacle when the latter is positioned therebeneath, and embodying a continuous side wall shaped conformably to the side wall of the receptacle, adapted when the unit is in its operative position to rest on, and form a continuation of, the receptacle side wall, and having at its upper end a structural member extending thereacross, a rotary crosshead disposed within the second mentioned side wall, an upstanding mulling wheel connected to the crosshead so that it is vertically movable to a limited extent relatively thereto, provided with spring means for urging it downwards, having the upper portion thereof disposed within the second

13

mentioned side wall and its lower portion disposed beneath said second mentioned side wall, and arranged so that during drive of the crosshead while the unit is in its operative position it travels in a circular course over the receptacle and effects mulling of the material by squeezing it against said receptacle, and means for driving the crosshead consisting of an electric motor and speed reducing gearing supported on said structural member.

11. A self-contained mulling unit of the character described comprising a cylindrical upstanding side wall provided at its upper end with a pair of parallel laterally spaced structural members extending thereacross, a rotary crosshead disposed within the side wall, a mulling wheel carried by the crosshead and positioned so that the upper portion thereof is disposed within in the side wall and its lower portion is disposed beneath said side wall, means for driving the crosshead consisting of an electric motor and speed reducing gearing positioned between, and supported by, said structural members, and an upstanding bail having the lower ends of the legs thereof connected to the central portions of said structural members, adapted to be attached to the hook of an overhead hoisting apparatus, and positioned and arranged so that when the unit is supported by said apparatus the side wall assumes a substantially horizontal position.

12. A self-contained mulling unit comprising a continuous side wall provided at its upper end with a pair of laterally spaced parallel structural members extending thereacross, a rotary crosshead disposed within the side wall and provided with a mulling element, power means for driving the crosshead consisting of an electric motor and speed reducing gearing positioned between and supported by, the structural members, and an upstanding bail having the lower ends of the legs thereof connected to the central

14

5 portions of said structural members, adapted to be attached to a hoisting apparatus, and positioned and arranged so that when the unit is supported by said hoisting apparatus said side wall assumes a substantially horizontal position.

13. A mulling apparatus comprising a rotary horizontally elongated crosshead, a bar disposed beneath and in parallel relation with the crosshead, a resilient block fitting between one end 10 of the bar and the superjacent end of the crosshead, a bolt extending through the block and said ends of the bar and crosshead and forming with the block a pivotal connection whereby the bar is supported so that it is capable of 15 swinging vertically, means between the other end of the crosshead and the distal end of the bar for limiting downward swing of said bar, an axle extending transversely of the bar and having the central portion thereof fixedly connected 20 to the central portion of said bar, mulling wheels rotatably mounted on the ends of the axle, and power means for driving the crosshead.

WALTER F. PIPER.
JOSEPH J. SOLDAT.
